Patented Mar. 13, 1973

226,473

DOOR BOLT LOCK

Louis G. Bobrowski, Berlin, Conn., assignor to The
Stanley Works, New Britain, Conn.

Filed Sept. 9, 1971, Ser. No. 179,255

Term of patent 14 years

Int. Cl. D8—07

U.S. Cl. D8—131

FIG. 4

FIG. 1

FIG. 3

FIG. 2

FIG. 5

FIG. 9

FIG. 6

FIG. 8

FIG. 7

FIG. 10

FIG. 1 is a front elevational view of one form of a door bolt lock showing my design;

FIG. 2 is a bottom plan view of the door bolt lock shown in FIG. 1;

FIG. 3 is a side elevational view;

FIG. 4 is a top plan view;

FIG. 5 is a rear elevational view;

FIG. 6 is a front elevational view of another form of a door bolt lock showing my design;

FIG. 7 is a bottom plan view of the door bolt lock shown in FIG. 6;

FIG. 8 is a side elevational view;

FIG. 9 is a top plan view; and
FIG. 10 is a rear elevational view.

I claim:

The ornamental design for a door bolt lock, as shown.
